UNITED STATES PATENT OFFICE

LUCIEN ANDUZE, OF LIMOGES, FRANCE, ASSIGNOR TO HERMAN C. KUPPER, INC., OF NEW YORK, N. Y., A CORPORATION OF NEW YORK

DESIGN FOR A TEAPOT OR SIMILAR ARTICLE

Application filed June 6, 1931. Serial No. 40,099. Term of patent 7 years.

To whom it may concern:

Be it known that I, LUCIEN ANDUZE, a citizen of the Republic of France, residing in the city of Limoges, in the Department of Hautevienne, France, have invented a new, original, and ornamental Design for a Teapot or Similar Article, of which the following is a specification, reference being had to the accompanying drawing, forming part thereof.

The figure is a side perspective view of a teapot, illustrating my new design.

I claim:

The ornamental design for a teapot or similar article as shown.

Signed at the city of Bordeaux, Department of Gironde, this 15th day of May, 1931.

LUCIEN ANDUZE.
